UNITED STATES PATENT OFFICE.

MARTIN S. BERNET, OF NEW YORK, N. Y.

DESIGN FOR A DOLL.

Application filed May 14, 1927. Serial No. 21,976. Term of patent 3½ years.

To all whom it may concern:

Be it known that I, MARTIN S. BERNET, a citizen of the United States, residing at borough of Manhattan, in the county of New York and State of New York, have invented a new, original, and ornamental Design for a Doll, of which the following is a specification, reference being had to the accompanying drawing, forming a part thereof.

The figure is a front view of a doll, showing my new design.

I claim:

The ornamental design for a doll, as shown.

MARTIN S. BERNET.
